Inventor;

George W. Gardanier.

UNITED STATES PATENT OFFICE.

GEORGE W. GARDANIER, OF BROOKLYN, NEW YORK.

POLARIZED RELAY FOR QUADRUPLEX TELEGRAPHS.

SPECIFICATION forming part of Letters Patent No. 275,185, dated April 3, 1883.

Application filed January 3, 1883. (No model.)

To all whom it may concern:

Be it known that I, GEORGE W. GARDANIER, a citizen of the United States, residing at Brooklyn, in the county of Kings and State 5 of New York, have invented certain new and useful Improvements in Polarized Relays for Quadruplex-Telegraph Systems; and I do hereby declare the following to be a full, clear, and exact description of the invention, such as will 10 enable others skilled in the art to which it appertains to make and use the same..

The invention relates to an improvement in polarized relays for quadruplex-telegraph systems; and it consists in a polarized relay provided with three armatures and adapted to operate substantially in the manner hereinafter described.

Referring to the accompanying drawing, which illustrates a plan view of my invention, 20 A denotes the permanent magnet, B the electro-magnet, and C D E the armatures, the two latter being provided with retractile springs a b. The magnets A B are of usual construction, and around the latter the wire d is wound 25 in the customary manner. The armature C passes between the ends of the electro-magnet B, and is acted upon by the current in said ends, being attracted in one direction by a negative current and in the opposite direction 30 by a positive current. The armatures D E extend from their bearings to suitable points in front of the ends of the electro-magnet B, and, as aforesaid, are supplied with the retractile springs a b. The armatures D E are secured 35 in such relation to the ends of the electro-magnet B as to render them susceptible to the influence of the current passing through the electro-magnet when said current is of sufficient strength to overcome the force of the retractile springs a b. The armature C is without a retractile spring, and will be affected by a weak current in the electro-magnet, as well as by a strong current, whereas the armatures D E will only be influenced by a strong current. 40 It will be observed, therefore, that a weak current will attract the armature C and that a strong current will influence both the armature C and one of the two armatures D E, according as the current is either positive or negative, the armature D responding to an increased negative current and the armature E to an increased positive current, or vice versa.

When a strong or an increased negative current is passing through the relay the armature C and the armature D will both be attracted toward the end e of the electro-magnet, and when a strong or an increased positive current is in the electro-magnet the armature C and the armature E will be attracted by the end f. A weak current, however, or one of only sufficient strength to vibrate the armature C, will permit the armatures D E to remain unaffected, while a current of increased strength will influence not only the armature C, but one of the armatures D E also. 65

The free extremity of the armature C is provided on opposite sides with the working-contact m and resting-stop n, and from the working-contact m a wire, p, passes to the electro-magnet t of the sounder F. From the pivoted 70 end of the armature C a wire, u, passes to the local battery w, and thence to the electro-magnet t, as indicated in the drawing.

The vibrating end of the armature D is between the working-contact x and resting-stop y, and the like end of the armature E is between the working-contact 1 and resting-stop 2. The working-contacts 1 and x are connected by the wire 3. From the pivoted ends of the armatures D E wires 4 and 5 pass to the electro-magnet 6 of the sounder 7, the wire 4 being in circuit with the local battery 8. 75

The operation of the invention is as follows: The main-line current, it will be understood, is passing through the wire d, with which the electro-magnet B is wound, and the object is to actuate the sounders F and 7 through the local wires from the single relay under the various conditions of the current passing through the wire d. For example, when a weak negative current is passing through the wire d the armature C will be drawn against the working-contact m, which completes the circuit through the armature, wires p u, battery w, and electro-magnet t, and has the effect of closing the sounder F. A weak positive current in the wire d draws the armature C against the resting-contact n, breaking the circuit at m, and permitting the retractile spring 9 to open the sounder F. The weak negative, or the weak positive current above mentioned being insufficient to overcome the tension of the retractile springs a or b, the armatures D and E are allowed to remain against the working-contacts 90 95 100

1 and x , and when they are in this condition, which is that illustrated in the drawing, the sounder 7 will be closed, a complete circuit being formed through the said armatures, the 5 wires 3 4 5, local battery 8, and electro-magnet 6. In case the current through the wire d is made an increased negative, the armature C will be drawn against the working-contact m , completing the circuit of and closing the sounder F, and at the same time, the strength of the 10 spring a being now overcome, the armature D will be moved from the working-contact x and against the resting-contact y , breaking the circuit of the sounder 7 at x and permitting the 15 spring 10 to open the said sounder. Upon the reversal of the polarity of the current last above described—*i. e.*, from an increased negative to an increased positive current—the effect is to open the sounder F by breaking its circuit at m , 20 and to break the contact of the armature E at 1, allowing the spring a to replace the armature D against its working-contact x and leaving the sounder 7 still open. In changing the increased positive to an increased negative current again, the sounder F is closed, the armature D is brought against the resting-stop y , 25 and the armature E is drawn against the working-contact 1 by the spring b . In altering the polarity of the current, if from a negative to 30 a positive, for instance, the contact of the armature E at 1 will be broken before the contact of the armature D at x is made, and if the current is changed from a positive to a negative the contact of the armature D at x will be 35 broken before the contact of the armature E at 1 is made; hence in either case the sounder 7 remains open and undisturbed.

From the foregoing it will appear plain that a weak negative current will close the sounder 40 F and not affect the then closed sounder 7; that an increased negative current will close the sounder F and open the sounder 7; that a

weak positive current will open the sounder F without affecting the then closed sounder 7; that an increased positive current will open 45 both sounders F and 7; that any change in the polarity merely of the increased current will not affect the sounder 7, and that a weak current of either polarity can only act upon the sounder F. 50

By the term "weak" current, as herein employed, I mean a current not having sufficient strength to actuate the armatures D E by overcoming the tension of the springs $a b$; and by the term "increased" current I mean one of 55 greater power than that exerted on the said armatures by the springs $a b$.

What I claim as my invention, and desire to secure by Letters Patent, is—

1. The polarized relay herein described, consisting of the permanent magnet A, electro-magnet B, and armatures C D E, the whole being arranged and adapted to operate substantially as set forth. 60

2. The polarized relay herein described, consisting of the permanent magnet A, electro-magnet B, and armatures C D E, the two latter being supplied with the retractile springs $a b$, substantially as set forth. 65

3. The polarized relay supplied with the armatures C, D, and E, in combination with the sounders F and 7, the wires $p u$, and local battery w , for closing the sounder F when the armature C is against its working-contact, and the wires 3 4 5 and local battery 8, for closing 70 the sounder 7 when the armatures D and E are against their working-contacts, substantially as set forth. 75

In testimony whereof I affix my signature in presence of two witnesses.

GEORGE W. GARDANIER.
